UNITED STATES PATENT OFFICE.

HUGH L. HAGAN, OF OAKLAND, CALIFORNIA, ASSIGNOR TO WHEEL O' FORTUNE SLIDE COMPANY, OF SAN FRANCISCO, CALIFORNIA, A CORPORATION OF CALIFORNIA.

STEREOPTICON SLIDE.

Application filed September 4, 1924. Serial No. 735,920.

The principal object of my invention is to provide a stereopticon slide which embodies a chance device, such as a spinner so that the operation of such device may be observed upon a screen onto which rays of light are projected through the slide.

Another object is to provide novel means for rotating the spinner when the chance device assumes this form.

10 With the foregoing in view, the invention resides in the novel subject matter herein-after described and claimed, the description being supplemented by the accompanying drawings.

15 Figure 1 is a side elevation partly in section.

Figure 2 is a horizontal sectional view as indicated by line 2—2 of Fig. 1.

20 Figure 3 is an enlarged detail horizontal sectional view illustrating one of the many different ways in which the spinner may be rotatably mounted.

25 The form of construction selected for illustration in the present application has been rather specifically described, with the understanding however that within the scope of the invention as claimed, numerous changes may be made.

30 The numerals 1 designate a pair of spaced, parallel transparent plates which are preferably formed of glass with their peripheral portions held against opposite sides of the spacing frame 2 or otherwise associated with a suitable spacing means. In the construction shown, the plates 1 are secured to the frame by binding tape 3.

35 Between the plates 1, a chance device is shown, said chance device being in the form of a spinner 4, evenly balanced and rotatably mounted in any suitable manner, as indicated at 5. One of the plates 1 preferably is provided with an annular series of numbers or other characters to co-act with the spinner, but in some instances these numbers might well be omitted, or if desired they can be placed on a separate piece of transparent material (not shown).

40 Formed through two adjacent side bars of the frame 2, there is shown a pair of air inlet passages 6 whose inner ends may well be provided with nipples 7 discharging in the plane of rotation of the spinner 4, in different directions and at points spaced about the circular path of said spinner. The outer

end of the passages 6 may well communicate with a nipple 8, and any suitable means such as a hand bulb 9 connected with this nipple by a tube 10, may be employed to create an inward blast of air through the passages 6 and nipples 7, so that the jet discharged from one or the other of these nipples will spin the spinner 4, regardless of the position in which said spinner may have stopped after its preceding operation.

45 While the pneumatic means above described, are preferably used for operating the spinner, other means could well be employed within the scope of the invention. Hence, I do not wish to be restricted to the use of such pneumatic means. Moreover, 70 while the chance device is preferably confined between two frame-carried plates, it will be understood that in a simple form of construction, it might be rotatably mounted at one side of a single plate, in which instance it could well be spun by hand.

50 The device is adapted to be placed in the usual slide holder of a stereopticon or other light ray projector, and the chance device is intended to be operated while rays of light are being projected through the glass plate or plates. Thus, an image of the rotating spinner or other chance device may be displayed upon a screen and the movements of said device clearly seen by an audience. The 80 point at which the spinner stops, visible to the entire audience, may well be used for determining any desired question. For instance, in moving picture theaters, it may be intended to give a free ticket to the holder of a "lucky number" such number to be determined by operation of the device, after giving patrons of the theater slips of paper with numbers printed thereon, before or after entering the theater. By determining 90 the lucky number before the entire audience, there can be no possible discussion as to the winner.

55 It may here be added that it is not absolutely essential to provide an air escape 100 from the space between the two transparent plates when the construction shown, is followed. There is of course a certain air leakage between the frame 2 and the plates and tape 3 which permits the escape of any air forced into the device by the bulb or the like. 9. If desired however, a gap 11 may be left in the tape, so as to permit air to more read-

ily escape, than if no positive vent were employed.

Excellent results may be obtained from the details disclosed and they may therefore well be followed, but within the scope of the invention as claimed, it may be embodied in numerous forms, as will be clear from the foregoing.

I claim:—

- 10 1. A device of the class described comprising a pair of spaced parallel transparent plates, a frame holding said plates in spaced relation for movement bodily into or from the slide holder of a light ray projector, a 15 chance device between said plates intended to be operated while light rays are being projected through the plates, whereby the operation of said chance device may be observed upon a screen, and means whereby air 20 is discharged between said plates and directly against said chance device for operating the same.

2. A device of the class described comprising a pair of spaced parallel transparent plates, a frame holding said plates in spaced relation for movement bodily into or from the slide holder of a light ray projector, a spinner mounted between said plates and intended to be operated while light rays are 25 being projected through the plates, whereby the movement of said spinner and its stopping point may be observed upon a screen, a plurality of spaced air passages extending into the space between the plates and dis- 30 charging in different directions in the plane of rotation of the spinner to act directly against the same, and means for creating a 35

blast of air through said passages to spin the spinner.

3. A chance device comprising a support, a spinner mounted thereon, a plurality of spaced air passages discharging in different directions in the plane of rotation of the spinner, and means for creating a blast of air through said passages and against the spinner to spin the same.

4. A device of the class described comprising a transparent plate adapted to be held in the slide holder of a light ray projector and a chance device comprising an annular series of indicating characters arranged on said plate and a spinner loosely pivoted on said plate for cooperation with said characters and adapted to be rapidly spun while the light rays are being projected through the plate, whereby the operation of the chance device may be observed upon a screen.

5. A device of the class described comprising a pair of spaced parallel transparent plates, a frame holding said plates in spaced relation, a spinner mounted between said plates, air inlet passages in said frame, nipples connected with the inner ends of said passages in position to discharge blasts of air in different directions in the plane of rotation of said spinner whereby the same is rapidly spun, a nipple connected with the outer end of said passages and means connected with said nipple for creating a blast of air through said passages and against the spinner.

In testimony whereof I have hereunto affixed my signature.

HUGH L. HAGAN.

ily escape, than if no positive vent were employed.

Excellent results may be obtained from the details disclosed and they may therefore well be followed, but within the scope of the invention as claimed, it may be embodied in numerous forms, as will be clear from the foregoing.

I claim:—

10 1. A device of the class described comprising a pair of spaced parallel transparent plates, a frame holding said plates in spaced relation for movement bodily into or from the slide holder of a light ray projector, a 15 chance device between said plates intended to be operated while light rays are being projected through the plates, whereby the operation of said chance device may be observed upon a screen, and means whereby air 20 is discharged between said plates and directly against said chance device for operating the same.

2. A device of the class described comprising a pair of spaced parallel transparent plates, a frame holding said plates in spaced relation for movement bodily into or from the slide holder of a light ray projector, a spinner mounted between said plates and intended to be operated while light rays are 30 being projected through the plates, whereby the movement of said spinner and its stopping point may be observed upon a screen, a plurality of spaced air passages extending into the space between the plates and dis- 35 charging in different directions in the plane of rotation of the spinner to act directly against the same, and means for creating a

blast of air through said passages to spin the spinner.

3. A chance device comprising a support, 40 a spinner mounted thereon, a plurality of spaced air passages discharging in different directions in the plane of rotation of the spinner, and means for creating a blast of air through said passages and against the 45 spinner to spin the same.

4. A device of the class described comprising a transparent plate adapted to be held in the slide holder of a light ray projector and a chance device comprising an annular series 50 of indicating characters arranged on said plate and a spinner loosely pivoted on said plate for cooperation with said characters and adapted to be rapidly spun while the light rays are being projected through the 55 plate, whereby the operation of the chance device may be observed upon a screen.

5. A device of the class described comprising a pair of spaced parallel transparent plates, a frame holding said plates in spaced 60 relation, a spinner mounted between said plates, air inlet passages in said frame, nipples connected with the inner ends of said passages in position to discharge blasts of air in different directions in the plane of rotation of said spinner whereby the same is rapidly spun, a nipple connected with the outer end of said passages and means connected with said nipple for creating a blast 65 of air through said passages and against the 70 spinner.

In testimony whereof I have hereunto affixed my signature.

HUGH L. HAGAN.
